UNITED STATES PATENT OFFICE.

GEORGE P. WIGGINTON, OF KALAMAZOO, MICHIGAN, ASSIGNOR TO KALAMAZOO LOOSE LEAF BINDER COMPANY, OF KALAMAZOO, MICHIGAN.

TEMPORARY BINDER OR LOOSE-SHEET HOLDER.

1,174,458.

Specification of Letters Patent.

Patented Mar. 7, 1916.

Application filed March 19, 1915. Serial No. 15,590.

To all whom it may concern:

Be it known that I, GEORGE P. WIGGINTON, a citizen of the United States, residing at Kalamazoo, Michigan, have invented certain new and useful Improvements in Temporary Binders or Loose-Sheet Holders, of which the following is a specification.

This invention relates to improvements in temporary binders or loose sheet holders. In the use of temporary binders for holding record sheets or leaves on which it is desired to keep the records in typewriting a binder which permits the ready removal and insertion of the sheets without injury or undue wear upon the sheets is of great advantage.

The main objects of this invention are: First, to provide an improved temporary binder or loose sheet holder which permits the rapid insertion or removal of the sheets or leaves from the binder and at the same time one in which the sheets are securely held when the binder is adjusted to clamp or retain the sheets, the sheets being freed when the binder is opened to release the sheets. Second, to provide an improved temporary binder having these advantages which is easy to manipulate and is simple and economical in structure.

Further objects, and objects relating to structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing, forming a part of this specification, in which:

Figure I is a horizontal longitudinal section through a structure embodying the features of my invention, a portion of the sheets being shown offset or in assorted relation to other sheets, taken on a line corresponding to line 1—1 of Fig. II. Fig. II is a vertical longitudinal section through a binder embodying the features of my invention, taken on a line corresponding to line 2—2 of Fig. I, the binder being closed. Fig. III is a vertical longitudinal section on a line corresponding to line 3—3 of Fig. I, the adjusting mechanism for the binding members or strips being omitted. Fig. IV is a plan view of removable binding posts of

different lengths. Fig. V is a detail longitudinal section corresponding to that of Fig. III, of a slightly modified construction, the modification being in the removable binding posts and the retaining means therefor. Fig. VI is a detail section on a line corresponding to line 6—6 of Fig. V, showing further details of the modified binding post. Fig. VII is a detail vertical longitudinal section corresponding to that of Fig. V, showing a further modification in the form of the binding post. Fig. VIII is a detail vertical longitudinal section corresponding to that of Figs. III, V, and VII, showing a further modification of the binding post portion of the binder. Fig. IX is a detail transverse section on a line corresponding to line 9—9 of Fig. VIII. Fig. X is a detail section on a line corresponding to line 10—10 of Fig. XI, showing my improvements applied to a post binder. Fig. XI is a detail section on a line corresponding to line 11—11 of Fig. X. Fig. XII is a detail section on a line corresponding to line 12—12 of Fig. X, showing details of the adjusting means. Fig. XIII is a detail view showing a modification similar to that of Fig. VIII, the post being arranged through one and threaded into the other of the post retaining bars.

In the drawings, similar reference characters refer to similar parts throughout the several views, and the sectional views are taken looking in the direction of the little arrows at the ends of the section lines.

Referring to the drawing, the covers 1 and 2 of the structure illustrated in Figs. I—IX inclusive, are formed with chambers to receive the adjusting mechanism of the binder. The clamping members 3 are pivotally mounted on the inner sides of the covers, the covers being provided with arm-like hinge members 4 which project into slots 5 in the binding members to receive the pivots 6. The binding strips or binding members 7 are arranged through the clamping members and extend into the covers. The arrangement of these parts is substantially that shown in the patent to Bushong, No. 851,276, April 23, 1907.

The adjusting mechanisms for the binding strips or members are arranged in the cover chambers 8, the binding strips being connected to the cross bar 9 adjustably supported by the screw rod 10 in the cover 1 and to the cross bar 11 adjustably mounted

on the rack bar 12 in the cover 2. This adjusting mechanism is substantially that shown in the Bushong Patent No. 878,340, Feb. 4, 1908. As the details of these mechanisms form no part of my present invention they are not further described herein.

The sheets or leaves 13 are provided with notches 14 adapted to receive the binding strips or binding members 7 and with holes 15 adapted to receive the binding posts 16. The notches 14 are open so that the sheets may be slipped over or lifted from the binding strips or members 7. The holes 15 are closed so that when the binding posts 16 are engaged therewith the sheets cannot be removed except as they are lifted from the ends of the posts or freed by the removal of the posts.

To removably secure the posts I provide the clamping members with sockets 17 in their inner faces adapted to receive the ends of the posts, as clearly shown in Fig. III. When the posts are inserted through the sheets and engaged with the clamping members and the clamping members drawn up by means of the adjustment of the binding members the sheets are securely retained. When, however, the clamping members are released and the posts removed the sheets are freed so that they can be freely manipulated. The posts are preferably tapered at their ends to facilitate insertion through the holes in the sheets and engagement with the clamping bars.

In the structure shown the covers are wider than the sheets and the sheets are provided with notches 14' which lie intermediate the binding members 7 when the notches 14 are engaged therewith and are adapted to engage one of the binding members when the sheets are offset as shown in Fig. I.

In the keeping of accounts or records it is sometimes desired to assort the sheets on which records are made for the day or of a certain class or group. This can be done by arranging the sheets in the offset relation shown. This facilitates the making up of balance sheets or reference to a particular class of sheets for any purpose.

In the modification shown in Figs. V and VI one of the clamping members 3 is provided with a threaded socket 18 for the threaded post 19, the other binding member being provided with a recess 20 adapted to receive the pivoted finger piece 21. This permits the ready removal of the post and at the same time the sheets are securely retained when the posts are inserted.

In the modification shown in Fig. VII the posts 19' are adapted for manipulation with a key.

In the modification shown in Fig. VIII I provide a pair of post retaining bars 22 having sockets 22' therein for the posts 16. These post retaining bars are provided with

pins 23 adapted to engage holes 24 in the clamping members 3, see Fig. IX. Fly sheets 25 are secured to the post retaining bars 21. The advantage of this modification is that it is applicable to structures now on the market without change other than forming the holes 24 for the pins 23.

In the modification shown in Fig. XIII the posts 43 are removably arranged through holes in one of the bars 22 and threaded into the other, the heads 43' of the posts being larger than the holes in the bar 22 through which the posts are arranged so that the sheets retained by the bars and posts may be removed from the binder. This is of advantage in the event that it is desired to use the bars and posts as a holder or binder for permanently filing the body of sheets. The posts can be readily removed freeing the sheets for manipulation as has been pointed out in connection with the other embodiments.

In Figs. X, XI and XII I show my improvements embodied in a post binder of a type in quite common use. In this embodiment the covers 26 are hinged to the clamping members 27 which have flanges 28 at their rear edges telescoping with the back 29. The back 29 constitutes a support for the adjusting screw 30 which is mounted in a center block 31 and oppositely threaded to engage the adjusting members 32. These adjusting members carry arms 34 which engage the inclined slides 35 on the clamping members so that when the adjusting members are moved outwardly by the screw the clamping members are separated. The clamping members are connected to the adjusting members by chains 36 arranged over pulleys 37 so that when the adjusting members are moved inwardly by the screw the clamping members are drawn together and clamped upon the sheets or leaves. As these adjustment features form no part of my present invention and are well understood in the art I do not describe them with further detail herein. The clamping members carry telescoping post members 38 and 39. The clamping members 27 are provided with opposed sockets 40 for the removable binding posts 16 which are preferably chamfered at their ends as in the other embodiments. The sheets are provided with open notches 42 to receive the telescoping binding posts and with holes 15 to receive the removable posts 16.

In the modification shown in Figs. X and XI the notches 42 are also disposed so that the sheets may be arranged in an aligned body, as shown in Fig. X, or in offset relation. The sheets may be offset in either direction.

In the embodiment shown in Fig. I when the binding strips are disengaged from the notches the notches and holes may be

brought into register or engaged with one of the posts for the purpose of providing a larger number of offset or selected groups. However, before the binder, including its 5 removable posts, can be completely adjusted to the sheets it is necessary that the slots and holes be brought into alignment.)

With the parts thus arranged the binder can be quickly manipulated to release or secure the sheets and when adjusted to secure or clamp the sheets they are securely retained, even though the clamping members are not tightly clamped on the sheets, at the same time when the clamping members are 10 released and the removable posts removed 15 the sheets are entirely freed, as stated.

I have not attempted to illustrate or describe all of the modifications which I contemplate or which might be desirable in adapting my improvements to a particular type of binder or to meet particular requirements as I believe the disclosures will enable those skilled in the art to which my invention relates to embody my improvements as 20 may be desirable. I desire, however, to be understood as claiming my improvements specifically in the form illustrated as well as broadly within the scope of the appended 25 claims.

Having thus described my invention, what I claim as new and desire to secure by Letters Patent, is:

1. In a temporary binder, the combination with sheets provided with slots adapted to receive binding strips and with holes adapted to receive binding posts, of covers, clamping members pivotally connected to said covers, said clamping members having opposed post sockets in their inner faces, 35 binding strips extending between said covers and adapted to engage the said slots of said sheets, said binding strips being arranged through said clamping members, means for adjusting said binding strips carried by said covers, and removable posts having tapered ends adapted to be arranged through said holes in said sheets and to engage said sockets in said clamping members.

2. In a temporary binder, the combination 50 with sheets provided with slots adapted to receive binding strips and with holes adapted to receive binding posts, of covers, clamping members pivotally connected to said covers, said clamping members having opposed post sockets in their inner faces, binding strips extending between said covers and adapted to engage the said slots of said sheets, said binding strips being arranged through said clamping members, means for 55 adjusting said binding strips carried by said covers, and removable posts adapted to be arranged through said holes in said sheets and to engage said sockets in said clamping members.

3. In a temporary binder, the combina-

tion with sheets provided with slots adapted to receive binding strips and with holes adapted to receive binding posts, of clamping members having opposed post sockets in their inner faces, binding strips extending between said clamping members, means for adjusting said binding strips, and removable posts having tapered ends adapted to be arranged through said holes in said sheets and to engage said sockets in said 70 clamping members.

4. In a temporary binder, the combination with sheets provided with slots adapted to receive binding strips and with holes adapted to receive binding posts, of clamping members having opposed post sockets in their inner faces, binding strips extending between said clamping members, means for adjusting said binding strips, and removable posts adapted to be arranged through 80 said holes in said sheets and to engage said 85 sockets in said clamping members.

5. In a temporary binder, the combination with sheets provided with slots adapted to receive binding strips and with holes 90 adapted to receive binding posts, of covers, clamping members pivotally connected to said covers, binding strips extending between said covers and adapted to engage the said slots of said sheets, said binding strips 95 being arranged through said clamping members, means for adjusting said binding strips, and binding posts adapted to be arranged through said holes in said sheets 100 removably associated with said clamping members.

6. In a temporary binder, the combination with sheets provided with slots adapted to receive binding strips and with holes adapted to receive binding posts, clamping 105 members, binding strips extending between said clamping members and adapted to engage said slots of said sheets, means for adjusting said binding strips, and binding posts adapted to be arranged through said 110 holes in said sheets removably associated with said clamping members, said posts being secured by the adjustment of said clamping members thereto by means of said binding strips.

7. In a temporary binder, the combination of clamping members having opposed post sockets therein, binding members extending between said clamping members, means for adjusting said clamping members, removable posts having tapered ends adapted to be engaged in said sockets in said clamping members, and sheets provided with slots adapted to receive said binding members and with holes adapted to receive 120 said binding posts.

8. In a temporary binder, the combination of clamping members having opposed post sockets therein, binding members extending between said clamping members, 125

- means for adjusting said clamping members, removable posts adapted to be engaged in said sockets in said clamping members, and sheets provided with slots adapted to receive said binding members and with holes adapted to receive said binding posts.
9. In a temporary binder, the combination of clamping members, binding members extending between said clamping members, means for adjusting said clamping members, binding posts removably associated with said clamping members, and sheets provided with slots adapted to receive said binding members and with holes adapted to receive said binding posts.
10. In a temporary binder, the combination of the covers, clamping members pivotally connected to said covers, said clamping members having opposed post sockets in their inner faces, binding strips extending between said covers, said binding strips being arranged through said clamping members, means for adjusting said binding strips carried by said covers, and removable binding posts having tapered ends adapted to be engaged in said sockets in said clamping members.
11. In a temporary binder, the combination of the covers, clamping members pivotally connected to said covers, said clamping members having post sockets, binding strips extending between said covers, said binding strips being arranged through said clamping members, means for adjusting said binding strips carried by said covers, and removable binding posts adapted to be engaged in said sockets in said clamping members.
12. In a temporary binder, the combination of covers, clamping members pivotally connected to said covers, binding strips extending between said covers, said binding strips being arranged through said clamping members, means for adjusting said binding strips carried by said covers, and binding posts removably associated in said clamping members.
13. In a temporary binder, the combination of clamping members, having opposed post sockets in their inner faces, binding strips extending between said clamping members, means for adjusting said binding strips, and removable binding posts having tapered ends adapted to be engaged in said sockets in said clamping members.
14. In a temporary binder, the combination of clamping members having post sockets, binding strips extending between said clamping members, means for adjusting said binding strips, and removable binding posts adapted to be engaged in said sockets in said clamping members.
15. In a temporary binder, the combination of clamping members, binding strips extending between said clamping members, means for adjusting said binding strips, and binding posts removably associated with said clamping members.
16. In a temporary binder, the combination of clamping members having opposed post sockets in their inner faces, binding members extending between said clamping members, means for adjusting said clamping members, and removable posts having tapered ends adapted to be engaged in said sockets in said clamping members.
17. In a temporary binder, the combination of clamping members having post sockets, binding members extending between said clamping members, means for adjusting said clamping members, and removable posts adapted to be engaged in said sockets in said clamping members.
18. In a temporary binder, the combination of clamping members, binding members extending between said clamping members, means for adjusting said binding members, and binding posts removably associated with said clamping members, said clamping members being provided with means coacting with said removable posts for supporting such posts against lateral movement in any direction.
19. In a temporary binder, the combination of clamping members having opposed post sockets in their inner faces, means for adjusting said clamping members, and removable posts adapted to be engaged in said sockets in said clamping members.
20. In a temporary binder, the combination of the covers, clamping members pivotally connected to said covers, binding strips extending between said covers, said binding strips being arranged through said clamping members, means for adjusting said binding strips carried by said covers, post retaining bars having post sockets therein and retaining pins, said clamping members having sockets adapted to receive said pins whereby said bars are supported on the inner face of said clamping members, and removable binding posts adapted to be engaged in said sockets in said retaining bars.
21. In a temporary binder, the combination of clamping members, binding strips extending between said clamping members, means for adjusting said binding strips, post retaining bars having post sockets therein and retaining pins, said clamping members having sockets adapted to receive said pins whereby said bars are supported on the inner face of said clamping members, and removable binding posts adapted to be engaged in said sockets in said retaining bars.
22. In a temporary binder, the combination of clamping members, means for adjusting said clamping members, post retaining bars having post sockets therein and retaining pins, said clamping members having sockets adapted to receive said pins whereby

said bars are supported on the inner face of said clamping members, and removable binding posts adapted to be engaged in said sockets in said retaining bars.

5 23. In a temporary binder, the combination of the covers, clamping members pivotally connected to said covers, binding strips extending between said covers, said binding strips being arranged through said clamping members, means for adjusting said binding strips carried by said covers, post retaining bars having post sockets therein mounted on the inner sides of said clamping members, and removable binding posts 10 adapted to be engaged in said sockets in said retaining bars.

24. In a temporary binder, the combination of clamping members, binding members extending between said clamping members, 20 means for adjusting said clamping members, post retaining bars having post sockets therein mounted on the inner sides of said clamping members, and removable binding posts adapted to be engaged in said sockets in said retaining bars.

25. In a temporary binder, the combination of clamping members, means for adjusting said clamping members, post retaining bars having post sockets therein mounted on the inner sides of said clamping members, and removable binding posts adapted to be engaged in said sockets in said retaining bars.

26. In a temporary binder, the combination of clamping members, binding members extending between said clamping members, means for adjusting said clamping members, post retaining bars mounted on the inner sides of said clamping members, and binding posts removably mounted on said retaining bars.

27. In a temporary binder, the combination of clamping members, means for adjusting said clamping members, post retaining bars mounted on the inner sides of said clamping members, and binding posts removably mounted on said retaining bars.

28. The combination in a loose leaf binder, of clamping members, binding strips extending between said clamping members, and posts removably associated with said clamping members, and sheets provided with a plurality of open notches in their binding edges spaced so that the sheets may be arranged in an aligned body or with part in an offset relation with their notches engaging the binding strips, said sheets having a plurality of holes uniformly spaced with said notches so that they register and are adapted to receive said removable posts when sheets are arranged in an aligned body or with part in an offset relation.

29. In a temporary binder, the combination of covers, clamping members connected to said covers, binding members extending

between said clamping members, binding posts removably associated with said clamping members, and sheets having notches open at their binding edges and holes adjacent their binding edges, said removable 70 posts being adapted to be engaged with said holes and said notches with said binding members to support selected sheets in an offset relation to the body of the sheets, the covers being of such width as to protect and 75 support such offset sheets.

30. In a temporary binder, the combination of covers, clamping members connected to said covers, binding members extending between said clamping members, binding posts removably associated with said clamping members; and sheets having notches open at their binding edges and holes adjacent their binding edges, said removable 80 posts being adapted to be engaged with said holes and said notches with said binding members to support selected sheets in an offset relation to the body of the sheets.

31. The combination with sheets having 90 notches open at their binding edges and holes adjacent their binding edges, of clamping members, binding members extending between said clamping members, the notches of said sheets being adapted to be engaged with said binding members, and a binding post removably associated with said clamping members and adapted to be inserted through said holes in said sheets.

32. The combination with sheets having 100 notches open at their binding edge and holes adjacent their binding edge, of clamping members having opposed post sockets, binding members extending between said clamping members, said notches being adapted to be engaged with said binding members, and a removable post adapted to be inserted 105 through said holes in said sheets and engaged in said sockets in said clamping members.

33. In a temporary binder, the combination 110 of binder members including covers, binding posts, at least one of said posts being removably associated with said binder members, and sheets having notches open at their binding edges and holes adjacent their binding edges, the removable post being adapted to be engaged with said holes, said notches being adapted to be engaged with a post whereby selected sheets may be supported in an offset relation to the body of the sheets, the covers being of such width as to protect and support such offset sheets.

34. In a temporary binder, the combination 125 of binder members, binding posts, at least one of said posts being removably associated with said binder members, and sheets having notches open at their binding edges and holes adjacent their binding edges, the removable post being adapted to be engaged with said holes, said notches being 130

adapted to be engaged with a post whereby selected sheets may be supported in an offset relation to the body of the sheets.

35. In a temporary binder, the combination of binder members including covers, a binding post and sheets having notches open at their binding edges and holes adjacent their binding edges disposed so that the sheets may be supported in an aligned body with the post engaging said holes or selected sheets supported in offset relation to the body of the sheets with their notches engaging the post, the covers being of such width as to protect and support such offset sheets.

36. In a temporary binder, the combination of binder members, a binding post, and sheets having notches open at their binding edges and holes adjacent their binding edges disposed so that the sheets may be supported in an aligned body with the post engaging said holes or selected sheets supported in an offset relation to the body of the sheets with their notches engaging the post.

37. The combination with binder members provided with opposed post sockets, of removable posts adapted to be engaged in said sockets, and sheets having notches open at their binding edges and holes adjacent their binding edges, said posts being adapted to be inserted through said holes in said sheets, said notches being adapted to be engaged with said posts so that the sheets so engaged are supported in an offset relation.

38. The combination with sheets having notches open at their binding edges and

holes adjacent their binding edges, of binder members, binding members extending between said binder members, said notches being adapted to be engaged with said binding members, and a post adapted to be inserted through said holes removably associated with said binder members.

39. A sheet or leaf for temporary binders provided with a plurality of open notches in its binding edge uniformly spaced so that sheets may be arranged in an aligned body or with part of the sheets in an offset relation with registering notches, said sheet being also provided with a plurality of holes adjacent its binding edge uniformly spaced relative to each other and relative to said notches so that there are registering holes when sheets are arranged in an aligned body or with part in an offset relation with their notches registering.

40. A leaf or sheet for temporary binders provided with a plurality of uniformly spaced notches open at its binding edge and a plurality of holes adjacent its binding edge uniformly spaced with each other and with said notches so that there are registering notches and registering holes when sheets are arranged in an aligned body or in a laterally offset relation.

In witness whereof, I have hereunto set my hand and seal in the presence of two witnesses.

GEORGE P. WIGGINTON. [L. S.]
